ROY D. CONWAY, OF CHATHAM, NEW JERSEY, ASSIGNOR TO WESTERN ELECTRIC COMPANY, INCORPORATED, OF NEW YORK, N. Y., A CORPORATION OF NEW YORK.

SIGNALING SYSTEM.

1,324,798.

Specification of Letters Patent. Patented Dec. 16, 1919.

Application filed May 24, 1917. Serial No. 170,609.

To all whom it may concern:

Be it known that I, ROY D. CONWAY, a citizen of the United States, residing at Chatham, in the county of Morris and State 5 of New Jersey, have invented certain new and useful Improvements in Signaling Systems, of which the following is a full, clear, concise, and exact description.

This invention relates to signaling systems, and more particularly to such systems in which a plurality of signaling devices may be controlled from a distance over a single circuit or over a plurality of circuits less in number than the number of 15 signaling devices.

In telegraph systems now in use, it is the practice to provide testing stations through which all telegraph lines, incoming to a large center, pass. In large cities 20 these testing stations are at times located in outlying sections of the city, while the central office may be more centrally located and several miles distant from the testing station. Should there be trouble on any of 25 the individual telegraph lines, it is always advisable that each individual telegraph station be able to signal the testing station in order that an attendant may come in on the line and locate and clear the trouble. In 30 the telegraph systems now in use, it is the practice to loop each telegraph line back from the individual telegraph station through the central office to the testing station at which it terminates. Signals at the 35 testing station individual to the telegraph lines are controlled over these separate looping lines, only one signal being controlled over each looping line. It will be seen, therefore, that, where the central office and the 40 testing station are several miles apart, this practice of providing a separate looping line for each individual telegraph line is very expensive. It is an object of this invention to provide a signaling system by means of 45 which the number of conductors required between the central office and the testing station will be decreased.

In accordance with a feature of this invention, a single conductor extending between the central telegraph office and the testing station is provided at each end with an automatic switch. At the testing station there is a signaling device corresponding to each individual telegraph line having access 55 to the single conductor. When wishing to

signal the testing station attendant, the apparatus at an individual telegraph station is actuated to cause apparatus located at the central office and individual to the telegraph line to be set, whereupon through the co-operation of the automatic switches and control apparatus, the signaling device corresponding to the signaling telegraph station is actuated. 60

For a more complete understanding of 65 this invention reference should be had to the following description taken in connection with the drawing showing a plurality of individual telegraph lines incoming through a testing station and a central telegraph office 70 to individual telegraph stations, and apparatus and circuits by means of which signaling devices located at the testing station and individual to the telegraph lines may be controlled from the individual telegraph 75 stations.

In the drawing, the apparatus shown to the right of dotted line 1-1 is located at the testing station A; that shown between the dotted lines 2-2 and 3-3 is located at the 80 central telegraph office B; that shown within the dotted rectangle C is located at an individual telegraph station local to the central office B and connected with a telegraph line 5; and that shown within the dotted 85 rectangle D is located at a distant telegraph station connected with the line 5. Three other telegraph lines 6, 7 and 8 similar to line 5 are shown in the drawing, but while for convenience the equipment of the line 5 90 only is indicated, the equipment of all lines is similarly equipped. A description of that of line 5 will be sufficient. At the distant station D, a telegraph relay 10 controlling a 95 sounder (not shown), a telegraph key 11 and a battery 12 are connected in series with line 5. The line 5 incoming from station D passes through both the testing station A and the central office B to the telegraph station C, and back to the central office B at which it terminates. At the station C, there is a telegraph key 13 and a relay 14, controlling a sounder (not shown), connected in series with the line 5, and a key 15 controlling a relay 16 at the central office B whose windings are connected in series opposing in the line 5. Since the windings of relay 16 are connected in series opposing, the actuation 100 of either telegraph key, which merely 105

opens the line, has no effect upon this relay. Each relay 16 controls the circuit of a relay 17 individual to the line and a relay 18 common to all lines. A relay 17, when energized, is locked up, and the common relay 18 when energized starts the control apparatus to cause the actuation of a signaling device at the testing station. A corresponding to the locked up relay 17, as will hereinafter 10 more fully appear.

An automatic switch comprising a plurality of fixed contacts or terminals 20, and a movable contact arm 21 normally held against a stop pin 22 and in engagement 15 with the first fixed terminal by the action of a coil spring 23 is located at the central office B and a similar switch is located at the testing station A. For convenience, the switch located at the central office B will be designated 20 as switch B and the switch located at the testing station will be designated as switch A. This contact arm 21 of each switch is adapted to be rotated in the direction of the arrow by means of stepping and 25 holding pawls 24 and 25 respectively controlled by stepping and releasing magnets 26 and 27, which pawls engage a ratchet wheel 28 with which the arm 21 moves.

Referring more particularly to the automatic switch B, the fixed terminal on which the contact arm 21 normally rests is connected by means of a conductor 29 through a resistance 30 to the armature of the relay 18 which is common to the telegraph lines. 35 This first terminal is included in the start circuit for the switch. The last fixed terminal is connected by means of a conductor 31 to the winding of a relay 32 which controls the release magnet 27 of the switch. Each 40 of the fixed terminals 20 of the switch is connected by a conductor 33 to a point on a conductor 34 between the relay 17 and a resistance coil 35. The first and last contacts or fixed terminals of the automatic switch A, 45 as will more fully hereinafter appear, serve to restore the apparatus of switch A to normal condition after its contact arm 21 has made a complete cycle. Each of the remaining fixed contacts or terminals of the switch 50 A is connected by means of a conductor 36 with a contact of a relay 37, which when energized locks up under control of a switch or key 38 to maintain a lamp 39 lighted.

Referring now to the operation of the signaling systems shown in the drawing, and assuming that the subscriber at the local telegraph station connected with the telegraph line 8 wishes to signal the testing station attendant, the key 15 at that station is 55 actuated to thereby short-circuit the right-hand winding of the differential relay 16 of line 8, which thereupon attracts its armature. Relay 17 individual to line 8 and the common relay 18 are thereupon actuated over a 60 circuit from battery through the contact of

actuated relay 16, winding of relay 17, conductor 34, resistance 35 and winding of common relay 18 to ground. Upon the actuation of relay 17 a locking circuit therefor and for the common relay 18 is established 70

through the contact of relay 17. Upon the energization of the relay 17, individual to line 8, the potential of the fifth fixed contact of the switch B is raised to approximately that of the battery in the circuit. 75

Relay 18, in operating, causes the actuation of a slow release relay 45 over a circuit from battery through the winding of slow release relay 45 and normal contact thereof, contact of relay 18, resistance 30, conductor 29, 80

first contact 20 of automatic switch B, contact arm 21, normal contact of a slow operating relay 46 and resistance 47 to ground. Relay 45, in operating, completes a locking circuit for itself from battery through the 85

winding of relay 45, left-hand alternate contact thereof and normal contact of relay 32 to ground. Relay 45, in operating, also prepares a circuit for relay 32, and closes the 90

break in a normally open signaling conductor 48 extending between the central office B and the testing station A. Upon the closure of the break in conductor 48, relays 50 and 70 are actuated over a circuit 95

from battery 51 (which preferably has a potential of approximately sixty volts) through the winding of relay 50, contact of slow operating relay 52, resistance 53, right-hand alternate contact of relay 45, conductor 48, windings of relays 70 and 71, right-hand 100

normal contact of differentially wound relay 72, and the normal contact of a slow release relay 73 to ground. Relay 71 is marginal and does not attract its armature when in 105

series with resistance 53, but does attract its armature when energized over the circuit with resistance 53 removed therefrom. Upon the actuation of relay 50, stepping magnet 26 and slow operating relay 46 are energized. 110

The stepping magnet 26 upon being energized attracts its armature, thereby causing stepping pawl 24 to engage a tooth of the ratchet wheel 28 and advance the ratchet wheel one step to thereby move the contact arm 21 from the first to the second fixed 115

terminal. Slow operating relay 46, upon being energized, attracts its armatures thereby causing the energization of the slow operating relay 52 over a circuit including the right-hand alternate contact of the slow operating relay 46. Relay 52, in operating, 120

opens the signaling conductor 48, thereby causing the release of relays 50 and 70. While the operations just described resulting 125

from the actuation of relay 50 were taking place, certain operations at the testing station A resulting from the actuation of relay 70 were also taking place. Relay 70, in attracting its armature, causes the energization of stepping magnet 26 of switch A. 130

thereby causing the associated stepping pawl 24 to engage a tooth of ratchet wheel 28 to move the contact arm 21 from the first to the second fixed terminal 20. Slow release relay 74 is also actuated to maintain an energizing circuit for slow release relay 75 which is normally energized over a circuit from battery through resistance 76, contact arm 21 and first fixed contact 20 of the switch A, normal contact of relay 74 and winding of relay 75 to ground, to prevent the actuation of a buzzer 77.

Upon the deenergization of relays 50 and 70 and the release of their armatures, the stepping magnets 26, 26 and relays 46 and 52 are deenergized and release their armatures. Relay 52, in releasing, closes the break in the signal conductor 48, whereupon relays 50 and 70 again operate and cause a repetition of the operations before described to advance the contact arm 21 of each switch from the second to the third fixed terminals. These cycles of operations continue until the contact arm 21 of switch B engages the fixed contact 20, the potential of which has been raised by the energization of the relay 17 individual to line 8, when, relay 46 being actuated, slow release relay 54 is actuated over a circuit from battery through the contact and winding of the locked up relay 17, conductors 34 and 33, the contact or fixed terminal engaged by the contact arm 21, left-hand alternate contact of relay 46 and the winding of relay 54 to ground. Relay 54, in operating, (1) opens its normal contact, which is in the operating circuit of relay 46 which is thereby deenergized; (2) closes, at its left-hand alternate contact, a short-circuiting path about resistance 53; (3) at its right-hand alternate contact closes a short-circuiting path about the locked up relay 17, which thereupon releases its armature. The short-circuiting path for the locked up relay 17 may be traced from battery through the right-hand alternate contact of relay 54, contact arm 21, engaged contact of the switch B to conductor 34. Relay 54, while being slow in releasing, is quicker in operating than the slow operating relay 52, so that resistance 53 is short-circuited before the signaling conductor 48 is opened at the contact of relay 52. Upon the short-circuiting of resistance 53, marginal relay 71 attracts its armature, thereby causing the energization of the relay 37 connected with the fifth contact over a circuit from battery through the contact of key 38, the lamp 39 and the winding of relay 37 in parallel, normal contact of relay 37, conductor 36, fifth contact of switch A, contact arm 21 thereof, and the contact of relay 71 to ground. Relay 37, in operating, establishes a locking circuit for itself through its alternate contact, thereby maintaining the lamp 39, corresponding to line 8 and to the contact of switch B whose potential had been raised, lighted and also maintaining the lamp and relay disconnected from the switch A until key 38 is actuated to release the locked up relay 37. Relay 54, hereinbefore referred to, in operating, also opens the circuit of relay 46, which then releases, opening the circuits of relays 52 and 54. These two relays now release; the former, relay 52, closing its normal contact; and the latter relay 54, removing the short circuit of resistance 53 and reestablishing the circuit of relay 46 which again operates. Since the relay 17 connected with contact engaged by the contact arm 21 is now released, relay 46, in operating, merely causes the operation of relay 52 to open the signaling conductor 48 to thereby cause the release of relays 50, 70 and 71. Both automatic switches continue stepping, and whenever contact arm 21 of switch B engages a contact the potential of which has been raised due to the energized condition of the associated relay 17, the relay 37 controlling the lamp 39 corresponding to such contact is actuated and the lamp is lighted.

The contact arm 21 of each switch is finally moved into engagement with last contact. Upon the engagement of contact arm 21 of switch A with its last contact, slow release relay 73 is actuated over a circuit from battery through resistance 76, contact arm 21 and last contact of switch A, winding of relay 73 and left-hand normal contact of the differentially wound relay 72 to ground. Relay 73, in operating, opens the signaling conductor 48 at the normal contact of relay 73, thereby permitting the release of relays 50 and 70, and also causes the energization of the differential relay 72 over a circuit from battery through the left-hand winding of relay 72 and left-hand alternate contact of relay 73 to ground. Relay 72, upon being energized, (1) opens its right-hand normal contact, introducing another break in the signaling conductor 48; (2) opens at its left-hand contact, the energizing circuit of slow release relay 73; (3) establishes a locking-circuit through its left-hand winding and its left-hand alternate contact; and (4) prepares a circuit through its right-hand winding which, when completed, as will hereinafter more fully appear, causes the deenergization of the differential relay and the consequent release of its armatures. The operation of relay 73 also causes the energization of release magnet 27 which withdraws the holding pawl from engagement with the ratchet wheel 28.

Since the stepping magnet 26 is now deenergized and the stepping pawl 24 is out of engagement with the ratchet wheel, the ratchet wheel is returned by the action of the spring 23 to normal position with the arm 130

21 resting against the stop pin 22. Upon the engagement of contact arm 21 of switch B with its last contact, relay 32 is actuated over a circuit from battery through the middle alternate contact of relay 45, winding of relay 32, conductor 31, the last contact of switch B, contact arm 21, left-hand alternate contact of relay 46, and winding of relay 54 to ground. Since the operation of relay 73 5 opened the signaling conductor 48, relay 50 has released its armature and the stepping magnet 26 of switch B and relay 46 now release their armatures and the stepping pawl 24 is, therefore, out of engagement with the ratchet wheel 28. An energizing circuit 10 is maintained for relay 32, for relay 45 is slow in releasing and resistance 47 is now substituted for the winding of relay 54. Relay 32, in operating, causes the energization 15 of the release magnet 27 which withdraws the holding pawl 25 from engagement with the ratchet wheel 28 and since the stepping pawl 24 is out of engagement with the ratchet wheel 28, the spring 23 restores the ratchet wheel 28 and contact arm 21 to normal 20 position with contact arm resting against the stop pin 22. Relay 32, in operating also causes the release of relay 45, which, assuming no relay 17 to be locked up 25 and the common relay 18 to be deenergized, remains released and maintains the signaling conductor 48 open at its right-hand alternate contact. Both release magnets 27 30 may be slow in releasing to insure the return of the arms 21 to normal position before the pawls 25 reengage the ratchet wheels.

When the slow release relay 73 has fully released its armatures and when the contact arm 21 of switch A reaches its normal position in engagement with the first fixed contact, a circuit is completed for the right-hand winding of differential relay 72 which may be traced from battery through resistance 76, contact arm 21, first contact, right-hand winding of differential relay 72, right-hand alternate contact thereof and normal contact of relay 73 to ground. Relay 72 is thereby deenergized and releases its armatures, whereupon all apparatus associated 40 with switch A is restored to normal position. If when the contact arms of the switches A and B are restored to their normal positions, the common relay 18 is energized, relay 45 due to the slow release thereof will 45 not fully release, for when during the release thereof the left-hand normal contact is closed, the original energizing circuit is closed at the contact arm 21 and the first contact of switch B. Relay 32 having by 50 this time released its armature, the locking circuit of slow release relay 45 is again established. Both switches will thereupon be moved through another complete cycle in 55 the same manner as before described.

As has been before mentioned, relay 75 is

normally energized when the contact arm 21 of switch A is in its normal position to maintain the operating circuit of buzzer 77 open, while the switches A and B are being stepped in synchronism, the contact of relay 75 is held open, for both relays 74 and 75 are slow releasing and do not release their armatures between impulses or while the armature of relay 74 is moving from the back to the front contact. If the contact 75 arm 21 of switch A be stopped on any contact but the first, relay 75 will be deenergized, closing the operating circuit of the buzzer 77, which is thereupon actuated and serves as a signal to the attendant that the 80 contact arm 21 of switch A is not in step with that of switch B.

What is claimed is:

1. A signaling system comprising a pair of automatic switches at separate points, a transmission line extending between such points, a plurality of signaling lines associated with the individual contacts of the one switch, a plurality of signals individual to the corresponding contacts of the other switch, means for driving the switches in synchronism in recurring cycles, means responsive to the closure of one of the signaling lines to cause the operation of said first-mentioned means as long as any signaling line is signaling, and means responsive to a connection by one switch with a signaling line to cause the display of the corresponding signal associated with the other switch without interrupting the operation of the 100 switch.

2. A signaling system comprising a pair of automatic switches at separate points, a transmission line extending between such points, a plurality of signaling lines associated with the individual contacts of the one switch, a plurality of signals individual to the corresponding contacts of the other switch, means for driving the switches in synchronism in recurring cycles, a relay 105 energized upon the closure of one of the signaling lines to cause the operation of said means as long as any signaling line is signaling, and means responsive to a connection by one switch with a signaling line to cause the display of the corresponding signal associated with the other switch without interrupting the operation of the switch.

3. A signaling system comprising a pair of step-by-step switches at separate points, a plurality of signaling lines associated with the individual contacts of the one switch, means operated upon the closure of one of the signaling lines for driving the switches in synchronism in recurring cycles as long as any signaling line is signaling, a plurality of signals individual to the corresponding contacts of the other switch, a relay individual to each signal, means operated upon the connection of the one switch 120 125 130

with a desired contact thereof to cause the simultaneous operation of the corresponding signal and the relay associated with the other switch, and a locking circuit for the 5 relay established upon the operation thereof to maintain said signal operated independent of any contact of said switch, thereby permitting the switch to pass through a complete cycle without interrupting the operation thereof.

4. A signaling system comprising a pair of automatic switches at separate points, a transmission line extending between such points, a plurality of signaling lines associated with the individual contacts of the one switch, a plurality of signaling devices individual to the corresponding contacts of the other switch, means responsive to the closure of one of the signaling lines for 10 driving the switches in synchronism in recurring cycles as long as any signaling line is signaling, means operated upon the connection of the one switch with the contact individual to the signaling line to vary the 15 resistance of the transmission line, and means associated with the other switch and responsive to the decrease in resistance of the transmission line to operate the signaling device associated with the corresponding 20 contact of the other switch and to maintain the same operated without interrupting the operation of the switch.

5. A signaling system comprising a pair of automatic switches at separated points, 25 a transmission line extending between such points, a plurality of signaling lines associated with the individual contacts of one switch, a plurality of signaling devices individual to the corresponding contacts of the other switch, means responsive to the closure of one of the signaling lines for 30 driving the switches in synchronism in recurring cycles as long as any signaling line is signaling, a relay operated upon the connection of one switch with the contact individual to the signaling line to vary the 35 resistance of the transmission line, and means responsive to the decrease in resistance thereof to operate the signaling device associated with the contact of the other switch without interrupting the operation of the switch.

6. A signaling system comprising an office, a finder switch thereat, a series of contacts 40 for the finder switch, means for altering the electrical potential of a desired one of the contacts, a second office, a plurality of signals thereat, one for each contact of the finder switch, an electrically operated switch 45 at the second office, a normally open line circuit joining the two offices, means responsive to the altering of the electrical potential of the desired one of the contacts for closing the line circuit, mechanism responsive to the closure of the line circuit for

50 moving the switches in synchronism, and a switching device responsive to the engagement of the finder switch with the electrically altered contact for actuating the signal corresponding thereto.

7. A signaling system comprising an office, a plurality of lines terminating thereat, a finder switch thereat common to the lines, a series of contacts for the finder switch, one corresponding to each line, means individual to and controlled from each line for altering the electrical potential of its corresponding contact, a second office, a plurality of signals thereat, one corresponding to each line terminating at the first 55 office, a normally open line circuit joining the two offices, a relay actuated due to the altering of the electrical potential of one of the contacts for closing the line circuit, means controlled over the line circuit 60 responsive to the actuation of the relay, to move the switches in synchronism, and apparatus responsive to the engagement of the finder switch with the electrically altered contact and coöperating with the electrically operated switch to actuate the signal corresponding to the engaged contact.

8. A signaling system comprising an office, a plurality of lines terminating thereat, a finder switch common to the lines, a series 65 of contacts for the finder switch, one for each line, a relay individual to each line, means associated with each line for actuating the relay individual thereto, the electrical potential of the contact corresponding 70 to a line being altered upon the actuation of the relay associated therewith, a second office, a plurality of signals thereat, one for each line terminating at the first office, means for moving the switches in synchronism, a relay at the first office actuated upon the engagement of the finder switch with the electrically altered contact to release the relay associated therewith, and a relay at the 75 second office responsive to the actuation of the relay at the first office and coöperating with the electrically operated switch to actuate the signal corresponding to the line associated with the previously energized individual relay.

9. A signaling system comprising a pair of switches at separate points, a plurality of signaling lines associated with the individual contacts of the one switch, a plurality of signals individual to the corresponding 80 contacts of the other switch, a normally open transmission line connecting the two separated switches, means operated due to the closure of one of the signaling lines to close the transmission line, means responsive to the closure of the transmission line for driving the switches in synchronism in recurring cycles as long as any signaling line is signaling, and means responsive to a connection by one switch with a 85

signaling line to cause the display of the corresponding signal associated with the other switch without interrupting the operation of the switch.

- 5 10. A signaling system comprising a pair of step-by-step switches at separate points, a plurality of signaling lines associated with the individual contacts of the one switch, a plurality of signals individual to the corresponding contacts of the other switch, a normally open transmission line connecting the two separated switches, a relay operated and locked up due to the closure of one of the signaling lines to close the transmission line,

a relay associated with each of the switches 15 and responsive to the closure of the transmission line to drive the switches in synchronism in recurring cycles as long as any signaling line is signaling, and a relay responsive to a connection by one switch with 20 a signaling line to cause the display of the corresponding signal associated with the other switch without interrupting the operation of the switch.

In witness whereof I hereunto subscribe 25 my name this 22nd day of May, A. D., 1917.

ROY D. CONWAY.
